UNITED STATES PATENT OFFICE.

ALLEN D. BORING, OF LAKELAND, FLORIDA.

RAILWAY TIME TABLE.

Application filed November 22, 1924. Serial No. 751,556.

It is customary in the operation of all railway systems to provide the employees with special time tables giving a list of all stations and trains on their respective divisions, the arrival and departure times of trains of all classes proceeding in either direction, the points at which sidings exist, the car capacities of such sidings, etc. Each division is divided into districts, and in printing the 10 time table, substantially each page thereof is devoted to one of these districts, although some pages cover more than one district. This page is provided at its center with a vertical column showing the names of all 15 stations on the district to which it relates, the right hand portion of the page is devoted to vertical columns giving arrival and departure times of all trains proceeding in one direction, and the left hand part of the 20 page is provided with similar columns for trains traveling in the opposite direction. These train columns are numbered according to the train numbers of the trains to which they are devoted, and if a trainman 25 wishes to determine at what time a train of a certain number will arrive at one particular station, he must locate the point at which a horizontal line from the station intersects the column assigned to the train about which 30 information is sought, and at this point, the desired information is given. Under the unfavorable conditions often existing,—poor light, strong air currents, pitching of train, etc.,—it is very difficult to properly read the 35 time table, particularly if it relates to a district over which a large number of trains travel, and obviously very serious accidents may result if an error is made. Furthermore, the present time tables are very often 40 torn and lost, causing inconvenience to both employee and management to obtain another copy even if such copies have not been exhausted.

The locomotive engineer must have and 45 refer to one of these time tables and not depend upon his memory with respect to trains which are approaching his train on a single track road and also trains which are superior or have the right of way 50 over his train on both single and double track roads. He usually keeps this time table in the box under his seat in the locomotive cab and it is a difficult matter 55 to refer to this many-paged large-sized time table under the unfavorable conditions existing in the cab. Furthermore, this oper-

ation consumes time during which he cannot have his eyes on the track ahead. It is therefore the primary object of my invention to provide a time table exhibitor 60 which is permanently and conveniently located for instant reference and by means of which the engineer may have constantly before his eyes as a reminder and reference, the information relative to approaching and 65 superior trains which must control him in the handling of his own train.

It is a further object of my invention to provide an improved form of time table which will effectively overcome all difficulties heretofore existing, and with these objects in view, the invention resides in the novel subject matter hereinafter described and claimed, the description being supplemented by the accompanying drawings. 75

Figure 1 is a front elevation of a cabinet containing two exhibiting aprons and adjusting means therefor.

Figure 2 is a vertical sectional view as indicated by line 2—2 of Figs. 1 and 4. 80

Figure 3 is a vertical sectional view as indicated by line 3—3 of Fig. 4, parts being omitted.

Figure 4 is a horizontal sectional view on line 4—4 of Fig. 3. 85

Figure 5 is a plan view of a portion of the exhibiting apron which displays columns of station names and certain data relating thereto.

Figure 6 is a plan view of a portion of 90 the other changeable exhibitor which contains columns indicating times for arrival and departure of trains, these columns being co-operable with the station columns of the first-named aprons. 95

The numeral 1 in the drawings, designates an exhibiting apron which contains vertical columns 2, showing all names of stations within a division of a railway system, each column being devoted to the station names within one district, it being of course understood that each of these districts, includes a predetermined length of the track, between two stations. In the present showing, the column 2, to the left 100 of the heavy line 3, contains the names of stations in the Lakeland-Fort Myers district of the Atlantic Coast Line, while the column 2 to the right of the aforesaid line 3, contains the names of stations in the 110 district between Sylvan Lake and Trilby. Adjacent the columns 2, I have shown aux-

iliary columns 4, 5, 6 and 7 which contain data relating to the numerous stations, such data being printed horizontally opposite the station names. In the column 4, numbers are placed which indicate at what stations sidings are to be found, as well as disclosing the car capacities of such sidings. In the columns 5 and 6, numbers are provided showing the distances of the stations from two other points on the railway, and in column 7, the minimum times allowed for making runs between stations, for certain classes of trains, are listed.

By any suitable means, I mount the apron 1 so that any of its columns 2 (and the adjacent columns 4, 5, 6 and 7) may be readily visible, and I provide a second apron 8 containing data co-operable with the station names of any of the columns 2 which may be displayed. This apron 8 is disclosed in Fig. 6, and it is provided with a plurality of areas 9 which, for the sake of illustration, I have separated by heavy vertical lines, one of which is shown at 10. In the central portion of each area 9, I provide a vertical column 2^a, each of these vertical columns being a duplicate of one of the vertical columns 2, of the apron 1. Immediately adjacent the column 2, I have shown auxiliary columns 4^a, 5^a, 6^a and 7^a which correspond to the columns 4, 5, 6 and 7 and may or may not be used on the apron 8. To the right of the zone occupied by the columns 2^a, 4^a, 5^a, 6^a and 7^a, vertical columns 11 are provided, said columns containing numbers showing the times of arrival and departure of all trains which proceed in one direction past the stations listed in the adjacent column 2^a, or the corresponding column 2 of the apron 1. To the left of the above-named zone, that is the zone occupied by the columns 2^a, 4^a, 5^a, 6^a and 7^a, I provide additional columns 11^a which are the same as the columns 11, except that they relate to trains proceeding in the opposite direction.

The apron 8 is mounted in proper relation with the apron 1, so that one of its columns 11 or one of its columns 11^a, as occasion may demand, may be brought into operative relation with the desired column 2 of the apron 1, as will be clear by reference to Fig. 1. For instance, if the train is progressing on the district of a railroad between Lakeland and Fort Myers, the apron 1 will be adjusted until the column 2 for that district of the track, is visible, as shown in Fig. 1. Next, the apron 8 is adjusted so that the station column 2^a thereof which corresponds to the displayed column 2, may be seen at either the right or the left of said column 2. The operator thus knows that any arrival or departure times given on the apron 8 at one side or the other of the column 2^a then on display,

relate to the column 2 which is being displayed. He may then turn the apron 8 in one direction or the other, until the number of the train in which he is interested, comes into view, the turning being done in one direction if the operator wishes to obtain information about a train traveling in one direction, while said apron is turned in the opposite direction if data is sought regarding a train traveling in the opposite way. Under the train number which has been brought into view in the manner just described, will appear one of the columns 11 or 11^a and by reading it in connection with the station names on the displayed column 2, the proper time of arrival or departure of the train in question, at any particular station, may be readily seen.

It will be seen from the above that the columns 2^a serve as means for identifying the columns 11 and 11^a, with the columns 2, with which they are intended to co-act, and while this means of identification is preferred, any other adequate provision could of course be made.

I have illustrated one of the ways in which the changeable exhibitors may be mounted. At 12, a vertically elongated cabinet has been shown, having a view opening 13 in its front. This cabinet may well be provided with a stationary lower end 14 and with an upper end 15 which is detachable by any suitable means, screws 16 being shown for this purpose. Within the cabinet 12 and rotatably connected with the upper and lower ends thereof, I have shown a pair of guide rollers 17 which are spaced inwardly from the vertical edges of the view opening 13, and behind these guide rollers 17, a pair of vertical winding rollers 18 are shown, said winding rollers being connected to the ends of the apron 1. Interposed between the rollers 17 and the vertical edges of the view opening 13, I provide two additional guide rollers 17^a, these rollers like the rollers 17 being flanged at their upper and lower ends. Behind the rollers 17^a and also behind the winding rollers 18, are two additional guide rollers 19, and preferably located behind these rollers, are two additional winding rollers 18^a. The ends of the apron 8 are connected with these winding rollers 18^a, and said apron passes forwardly from them, around the front sides of the guide rollers 17^a, and then passes rearwardly around the rollers 19.

The upper ends of the rollers 18 and 18^a are provided with trunnions 20 which are rotatably received in bearing sockets 21, formed in the lower side of the upper end 15 of the cabinet 12, while the lower ends of said rollers are provided with non-circular extensions 22 which are receivable in similarly shaped sockets 23 in heads 24 on the upper ends of operating shafts 25. These

shafts pass rotatably through openings in the lower end 14 of the cabinet and are provided with knobs 26 on their lower ends to be turned at will. Between these knobs and the cabinet end 14, suitable expansive, spring devices 27 are located to force downwardly on the shafts 25 and hold their heads 24 frictionally against the cabinet end 14, so that the two aprons 1 and 8 will be adequately held in any position to which they may be turned. However, by turning the knob 26 at one end of either apron to wind the latter, it will be seen that such apron is free to unwind at its other end, the adjacent head 24 then moving upon the cabinet end 14, but constantly exerting a frictional braking action to prevent the unwinding of any surplus of the apron.

Whenever any changes are made in the number of trains running, the times at which said trains arrive or depart, etc., requiring the substitution of new aprons for the aprons 1 and 8 previously used, the upper end 15 of the cabinet may be removed, thus permitting the rollers and the associated aprons to be readily removed so that the new ones may be substituted.

In order that the improved time table may be readily viewed at night, when passing through tunnels or in other dark places, I preferably provide means for illuminating it, and for illustrative purposes, I have illustrated an electric bulb 29, within the cabinet. Obviously, for an engineer's use, this cabinet may be suitably mounted in the locomotive cab, while for the use of other trainmen, it may be carried by any portion of the train. Similarly, any desired number of the devices may be mounted in the offices and stations, to be used at will, by the railway officials.

As excellent results are obtainable from the general association herein disclosed, such association may well be followed. However, within the scope of the invention as claimed, numerous modifications may be made.

It will be noted that by the use of my invention, considerable time will be saved in getting the desired information from the time table in both the office and on the train, but it is of especial value to the locomotive engineer upon whom so much depends with respect to the safety of the train. The engineer without having to waste time to locate and to refer with difficulty to the usual time table, will have in a fixed position before his eyes, the important data relating to approaching and superior trains which should control the operation of his train. Because this information is constantly before him, it serves as a reminder and thus tends to reduce accidents.

I claim:—

1. A railway employee's time-table com-

prising a changeable exhibitor containing columns of station names and adapted to display any one column to view, and additional independently changeable exhibiting means adjacent the first-named exhibitor, 70 said additional exhibiting means containing columns of legends co-operable with the station columns and indicating times of arrival and departure for trains at the stations named in the station name columns, the 75 legends pertaining to any station name being opposite such name, said additional exhibiting means having means for identifying its columns with the station columns with which they are to co-act, and including 80 simultaneously changeable exhibiting portions displaying the times of arrival and departure of trains proceeding in opposite directions.

2. A railway employee's time-table comprising a changeable exhibitor containing columns of station names and adapted to display any one column to view, and additional independently changeable exhibiting means adjacent the first-named exhibitor, 85 said additional exhibiting means containing columns of legends co-operable with the station columns and indicating times of arrival and departure for trains at the stations named in the station name columns, the 90 legends pertaining to any station name being opposite such name, said additional exhibiting means having means for identifying its columns with the station columns with which they are to co-act, and including 95 simultaneously changeable exhibiting portions displaying the times of arrival and departure of trains proceeding in opposite directions.

3. A railway employee's time-table comprising a changeable exhibitor containing columns of station names and adapted to display any one column to view, and additional independently changeable exhibiting means adjacent the first-named exhibitor, 100 said additional exhibiting means containing columns of legends co-operable with the station columns and indicating times of arrival and departure for trains at the stations named in the station name columns, the 105 legends pertaining to any station name being opposite such name, said additional exhibiting means having means for identifying its columns with the station columns with which they are to co-act, and including 110 simultaneously changeable exhibiting portions displaying the times of arrival and departure of trains proceeding in opposite directions.

4. A railway employee's time-table comprising a changeable exhibitor containing columns of station names and adapted to 115 display any one column to view, and addi-

tional independently changeable exhibiting means adjacent the first named exhibitor, said additional exhibiting means containing columns of legends co-operable with the station columns and indicating times of arrival and departure for trains at the stations named in the station name columns, the legends pertaining to any station name being opposite such name, said additional exhibiting means having two simultaneously changeable exhibiting portions displaying the times of arrival and departure of trains proceeding in opposite directions; having identifying means consisting of columns of station names identical with the station name columns of the first-named exhibitor, the station names of said additional exhibiting means being alined with the same names on said changeable exhibitor and all arrival and departure legends relating to one station column of the additional exhibiting means being grouped adjacent said column on said means; said additional exhibiting means also containing data opposite names of stations giving the car capacities of sidings at such stations.

5. A device of the class described comprising an elongated cabinet having a view opening in its front a pair of guide rollers disposed longitudinally in the cabinet in inwardly spaced relation with the edges of said view opening, a pair of winding rollers behind said pair of guide rollers, an apron connected to said winding rollers and trained around the guide rollers, said apron extending straight from one of said guide rollers to the other; a second pair of guide rollers between the first named guide rollers and the edges of the view opening, a third pair of guide rollers in the casing, and a second apron connected to said second pair of winding rollers, said second apron being trained around the second and third pairs of guide rollers and extending in front of the second pair; and means for turning the winding rollers of either apron independently of the other apron.

6. A device of the class described comprising an elongated cabinet having a view opening in its front, a pair of guide rollers disposed longitudinally in the cabinet in inwardly spaced relation with the edges of said view opening, a pair of winding rollers behind said pair of guide rollers, an apron connected to said winding rollers and trained around the guide rollers, said apron extending straight from one of said guide rollers to the other; a second pair of guide rollers between the first named guide rollers and the edges of the view opening, a third pair of guide rollers, a second pair of winding rollers in the casing, and a second apron connected to said second pair of winding rollers, said second apron being trained around the second and third pairs of guide rollers and extending in front of the second pair; and means for turning the winding rollers of either apron independently of the other apron.

6. A device of the class described comprising an elongated cabinet having a view opening in its front, a pair of guide rollers disposed longitudinally in the cabinet in inwardly spaced relation with the edges of said view opening, a pair of winding rollers behind said pair of guide rollers, an apron connected to said winding rollers and trained around the guide rollers, said apron extending straight from one of said guide rollers to the other; a second pair of guide rollers between the first named guide rollers and the edges of the view opening, a third pair of guide rollers, a second pair of winding rollers in the casing, and a second apron connected to said second pair of winding rollers, said second apron being trained around the second and third pairs of guide rollers and extending in front of the second pair; and means for turning the winding rollers of either apron independently of the other apron.

In testimony whereof I have hereunto affixed my signature.

ALLEN D. BORING.
